CLAIM

The ornamental design for a telephone set, as shown and described.

DESCRIPTION

FIG. 1 is a front perspective view of a telephone set showing our new design in cradled relationship;
FIG. 2 is a left side and front perspective view thereof;
FIG. 3 is a right side perspective view thereof;
FIG. 4 is a right side and rear perspective view thereof;
FIG. 5 is a top perspective view thereof;
FIG. 6 is a bottom perspective view thereof; and
FIG. 7 is a bracket associated perspective view of the rear of the handset removed from and positioned in front of the stand component of the telephone set.

FIG. 1

FIG. 2

FIG. 3

FIG. 4

FIG. 5

FIG. 6

FIG. 7
